CUTTING DEVICE

Charles F. Bowersett, Laurel, Md.

Application January 10, 1951, Serial No. 205,395

6 Claims. (Cl. 126—263)

(Granted under the act of March 3, 1883, as amended April 30, 1928; 370 O. G. 757)

1

This invention relates generally to cutting apparatus and more particularly to a flexible thermite element adapted for wrapping about a stranded cable or wire to be cut and whereupon as the element is ignited the cable is separated in such a manner that the strands thereof at the respective ends of the cut are so fused that subsequent fraying or brooming of the ends of the cable is thusly prevented.

The apparently simple operation of cutting stranded cable in the field whereupon the ends of the cable are to be secured against fraying as by fusing, can become quite difficult particularly when conducted atop a pole or at some remote location to which conventional bulky cutting apparatus must be carried long distances and possibly by pack over rough terrain to provide for such a cutting operation.

Whereas, acetylene and oxygen torches have been heretofore employed almost exclusively for the purpose of securing stranded cable and concurrently fusing the ends thereof the instant device provides for a simple arrangement of thermite pellets or beads so strung upon a supporting wire therefor that as the wire is wound about the cable to be cut the pellets are held snugly against the cable in such a manner that as the pellets burn, following their ignition, the cable is severed with the strands thereof becoming integrally fused together whereby fraying of the cable ends is prevented.

The present invention further provides for a light and compact element for cutting stranded cable or the like that may be easily carried in quantity in the pocket of a lineman and by reason of it being relatively inexpensive to manufacture may be included as conventional equipment in expendable work and repair kits whereby as more expensive cutting apparatus for this purpose would be economically prohibitive.

It is an object of the present invention to provide a new and improved cable cutting thermite element flexible for winding about the cable to be cut and whereby the strands of the cable are fused at the ends of the cut by the burning of the element.

An additional object is to provide a flexible slow-burning thermite element wherein a soft malleable wire maintains the element in closely wound adjacency about the cable to be cut by the burning of said element.

A still further object is to provide a slow-burning high-temperature segmented element wherein in a soft malleable wire is centrally arranged within interlocking segments of the element for

maintaining the element in closely wound position about a stranded cable to be cut by the burning of said element.

Other objects and many of the attendant advantages of this invention will be readily appreciated as the same becomes better understood by reference to the following detailed description when considered in connection with the accompanying drawings wherein:

10 Fig. 1 is a view in elevation of the thermite element of the present invention as shown wound about a section of a stranded cable to be cut by the burning of the element;

15 Fig. 2 is a view in elevation of the stranded cable after having been severed by the burning of the thermite element and with the ends of the cable shown as fused together; and

20 Fig. 3 is a view partly in section and partly in elevation of the thermite element in an extended position and showing the arrangement therein of the igniting charge and the exothermic charge as arranged upon the malleable supporting wire therefor.

25 Referring now to the drawings and more particularly to Fig. 3 thereof the thermal cutting element 5 of the present device is shown therein to include a cylindrically formed casing or covering 6 which may be either formed from extruded material such, for example, as plastic or which may be woven from fabric as shown herein and thereafter suitably waterproofed either before or after assembly, as desired.

30 Secured within the end 16 of the casing is a conventional fuze element 7 about which the casing is tightly drawn as by the cord 8. Obviously a clip or any other suitable means, not shown, may be employed, if desired, for securing the casing about the fuze and thereafter this end of the casing may be waterproofed as by dipping in paraffin or the like. The fuze 7 is adapted

35 when ignited, as by a match, to effect the burning of a powder or igniting charge 9, Fig. 3, arranged within the end 16 of the casing and within which the inner end of the fuze 7 is buried.

40 Abutting the charge 9 and ignitable thereby is the end of a chain of relatively slow burning pellets or beads 10 formed from any suitable exothermic material such, for example, as "thermite" and maintained in proper alignment within the casing as by a centrally arranged soft metallic rod 11 over which the pellets are preferably threaded or strung before insertion thereof within the casing 6. By reason of the concave and convex formation of the respective ends

50 12 and 13 of the pellets 10, respectively, there

is provided an arrangement whereby the element 5 may be easily bent for winding about a cable 15 to be cut while the pellets are maintained at all times in closely fitting adjacency whereby their progressive burning may not be impaired.

The centrally arranged wire 11, which may be formed from any suitable malleable material such, for example, as soft iron or the like, provides that the element 5 when wound about the cable 15 to be cut, Fig. 1, is held closely thereto with the wire further providing means for preventing the element 5 falling apart prematurely during the burning of the pellets 10 thereof. After the assembly of the element 5, the end 17 may be waterproofed as by dipping in paraffin in a similar manner to the fuze equipped end 16 thereof and whereby the assembly is now completely moistureproof.

It will be understood that, if desired, the exothermic charge or pellets 10 may be in the form of thermite granules loosely packed within the casing 6 whereby the casing may be easily bent or wound about the cable to be cut. The primary disadvantage of such an arrangement over that shown herein by the pellets 10 is that the thermite when in a granular form will have a tendency to spill from the casing during the burning thereof rather than be held closely to the cable as provided by the arrangement herein set forth.

Whereas, in Fig. 3 the charge 9 is shown adapted for ignition by the fuze 7, it is understood that, if desired, a detonator or match assembly may be provided interchangeably for the purpose.

As the cable 15 is cut by the burning thereon of the element 5 the ends 18 and 19 of the cable are so fused, as illustrated in Fig. 2, that subsequent fraying or brooming of the cable strands 20 is thereafter prevented.

Obviously many modifications and variations of the present invention are possible in the light of the above teachings. It is therefore to be understood that within the scope of the appended claims the invention may be practiced otherwise than as specifically described.

The invention described herein may be manufactured and used by or for the Government of the United States of America for governmental purposes without the payment of any royalties thereon or therefor.

What is claimed as new and desired to be secured by Letters Patent of the United States is:

1. A flexible exothermic cable cutting device of the character disclosed for wrapping about a cable to be cut and comprising, in combination, a casing, means for maintaining the casing in wrapped relationship about the cable, an igniting charge arranged in one end of said casing, means for igniting said charge, and a quantity of exothermic material arranged within said casing and disposed adjacent said charge for ignition thereby.

2. An exothermic cable cutting device of the character disclosed adapted for wrapping about a cable to be cut thereby and comprising, in combination, an elongated flexible casing, an igniting charge arranged in one end of said casing, an exothermic mixture arranged for ignition by said charge and disposed substantially along the length of said casing, and a soft malleable rod arranged within said casing substantially along the length thereof for maintaining said device in closely fitting wrapped adjacency about the cable to be cut by the burning of said mixture.

3. An exothermic filled cutting device of the character disclosed adapted for wrapping about a stranded cable to be cut and comprising, in combination, an elongated flexible casing, means for maintaining the casing in intimate contact with the cable after wrapping thereabout, an ignition charge arranged in one end of said casing, fuze means for igniting said charge and extending outwardly from the said one end of said casing, and a plurality of exothermic elements linearly arranged within and extending substantially along the length of said casing and ignitable by burning of said charge.

4. An exothermic cable cutting device of the character disclosed adapted for wrapping about a stranded cable to be cut and comprising, in combination, an elongated waterproof flexible casing, an ignition charge arranged in one end of said casing, means extending outwardly from said one end of said casing for igniting said charge, a malleable rod arranged within said casing and extending substantially throughout the length thereof for maintaining the device closely wrapped about said cable, and a plurality of perforated exothermic pellets arranged within said casing and strung upon said rod.

5. An exothermic cable cutting device of the character disclosed adapted for wrapping about a stranded cable to be cut and comprising, in combination, an elongated flexible casing, a length of malleable rod arranged centrally in and substantially throughout the length of said casing, a plurality of concavo-convex exothermic elements in nested relationship threaded upon said rod, an igniting charge for said elements arranged in one end of said casing and in adjacency to said elements and means extending outwardly from said casing for igniting said charge.

6. An exothermic cable cutting device of the character disclosed adapted for wrapping about a cable to be cut and comprising, in combination, an elongated flexible casing, an igniting charge arranged in one end of said casing, a length of flexible rod centrally arranged within said casing and charge for maintaining said device tightly wrapped about said cable, a plurality of concavo-convex exothermic elements linearly arranged in nested relation within said casing and strung upon said rod and ignitable progressively in successive order by said charge, and means for closing the other end of said casing.
